UNITED STATES PATENT OFFICE.

FRANK E. VANDERCOOK, OF WATERBURY, CONNECTICUT, ASSIGNOR OF ONE-HALF TO JOHN MEYER, OF WATERBURY, CONNECTICUT.

SHOE-LACING HOOK.

SPECIFICATION forming part of Letters Patent No. 699,989, dated May 13, 1902.

Application filed October 17, 1901. Serial No. 78,966. (No model.)

To all whom it may concern.

Be it known that I, FRANK E. VANDERCOOK, a citizen of the United States, and a resident of Waterbury, in the county of New Haven and State of Connecticut, have invented certain new and useful Improvements in Shoe-Lacing Hooks, of which the following is a specification.

My invention relates to new and useful improvements in shoe-lacing hooks, and more particularly to a guard or shield for protecting the open end of such hooks.

It is the object of my invention to provide a shoe-lacing hook for either gentlemen's or ladies' shoes, which hooks may be applied and used in the customary way; further, to produce one which will not have any projecting points or raw edges to engage the overhanging garments of the wearer, as is now the objectionable result with the majority of hooks upon the market.

My invention may be applied to several forms of lacing-hooks by a slight change; but in all instances each hook would be made and attached separately, as is now the custom, and fastened by riveting or eyeleting in the usual way.

With the above objects in view my invention resides and consists in the novel construction and arrangement of parts shown upon the accompanying sheet of drawings, forming a part of this specification, upon which similar characters of reference denote like or corresponding parts throughout the several figures, and of which—

Figure 1 shows a central vertical cross-section of a shoe-lacing hook formed in accordance with my invention. Fig. 1^a is a plan view of Fig. 1. Figs. 2 and 3 show a central vertical cross-section and a plan view, respectively, of a hook similar to that shown in Fig. 1, with a slightly-modified method of attaching the shield. Figs. 4 and 5 show a central vertical cross-section of a modified form of lacing-hook, the same comprising in part several suitable eyelets instead of but one, as in the preceding figures. Figs. 6, 7, and 8 show a plan view, a side, and front elevation, respectively, of a further modification of my lacing-hook, the same being designed in accordance with the popular forms of hooks

upon the market, but provided with my improved guard.

Referring in detail to the characters of reference marked upon the drawings, *a* represents the main stud of my hook, which may be made solid of a single piece, as shown in Figs. 1, 2, and 3, or it may be constructed of one or more eyelets, as shown in Figs. 4 and 5. This stud in practice forms the engagement for the lacing-string when the latter is looped around it in the customary manner.

In Fig. 6 a shorter stud *a'* is employed, and to the upper end is secured a stud *b'*, having an enlarged head *c'*, which differs but slightly from the lacing-hooks now in common use and is designed to be produced upon some of the automatic machines now employed for manufacturing such hooks.

My improvement consists, briefly, in providing a flexible shield *d* for the stud, which may be constructed of rubber or thin metal and is preferably attached to the head of stud, as shown in the several drawings, in a manner to cover the raw edge of the head and inclose the opening thereunder. In Fig. 1 this shield is shown in plan view as being substantially round, presenting a smooth round oval head-surface with edges deflected downward, which come nearly in contact with the surface of the shoe if attached thereto. In Fig. 1^a I have shown the edge of this shield cut out in two places, forming openings in which the lace is designed to lie, thus avoiding any folding of the shield and insuring a more presentable article. These openings are not in all cases necessary, since if the shield is formed of sufficiently thin rubber of proper quality it will snugly engage the string and not produce a bad effect.

In Figs. 6, 7, and 8 I have shown a simple and inexpensive form of shield, which may also be formed of rubber, and consists of a top portion, which in practice is molded or otherwise attached to the head *c* of the hook *b'* and is provided with a tapering depending apron *d'*, the end of which nearly engages the face of the stud. These shields, as will be seen in each instance, completely cover the head of the stud, producing a smooth and slight appearance to the finished article, besides preventing any possible engagement of the stud with the gar-

ments of the wearer. At the same time they are so constructed that the lacing may readily be drawn in past the flexible apron against the stud, which apron quickly snaps back to 5 its normal position after the lacing is drawn up in place.

The same method of lacing would be employed in using either of the forms of studs shown and would be accomplished by simply 10 drawing the lace around and under the flexible shield shown, all of which can be done as quickly as if using the present plain lacing stud.

Having thus described my invention, what 15 I claim as new, and desire to secure by Letters Patent, is—

1. In a shoe-lacing device, the combination with a lacing-stud, of an annular depending flexible apron for the same covering the stud 20 and adapted to fold under to permit the lac-

ing to pass thereby for engagement with the said stud.

2. A shoe-lacing device comprising a stud having an annular projecting yieldable extension secured thereto covering the entrance 25 to the hook and provided with suitable notches in its periphery forming string-pockets.

3. A shoe-lacing device comprising a stud having an enlarged head integral therewith, a covering for said head with a depending 30 flexible apron inclosing the entrance to the stud.

Signed at Waterbury, in the county of New Haven and State of Connecticut, this 12th day of October, A. D. 1901.

FRANK E. VANDERCOOK.
